CLAIM

The ornamental design for a chicken feeder, as shown and described.

DESCRIPTION

FIG. 1 is a top, side, and front perspective view of a chicken feeder, showing our new design;

FIG. 2 is a bottom, side, and front perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is an exploded view of the chicken feeder of FIG. 1. The broken lines shown in the drawings depict portions of the chicken feeder that form no part of the claimed invention.
